(57) **CLAIM**

The ornamental design for a diesel fuel tank as shown and described.

DESCRIPTION

FIG. 1 is a front perspective view, right perspective view, and top perspective view of a diesel fuel tank, showing my new design;

FIG. 2 is a front perspective view, left perspective view, and top perspective view thereof;

FIG. 3 is a front elevational view thereof;

FIG. 4 is a rear elevational view thereof;

FIG. 5 is a left side view, the right side view being a mirror image of FIG. 5; and,

FIG. 6 is a top plan view thereof.

The broken lines in the figures are for the purposes of illustrating portions of the diesel fuel tank, which form no part of the claimed design.
